[57] CLAIM

The ornamental design for a corrugated pallet, as shown and described.

DESCRIPTION

FIG. 1 is an inverted perspective view of a corrugated pallet made in accordance with the present invention;

FIG. 2 is a top plan view showing the corrugated pallet of FIG. 1 showing the edges of the hollow, generally square support members therein;

FIG. 3 is an end elevational view showing the corrugated pallet of FIG. 1 and,

FIG. 4 is a bottom plan view showing the corrugated pallet of FIG. 1; and,

FIG. 5 is a side elevational view showing the corrugated pallet of FIG. 1, the other side being a mirror image.
